Anderson P. H. Jordan. Madison, ^{ala} Tenn.

Letters Patent

The Schedule referred to in these Letters Patent and making part of the same containing a description in the words of this said Anderson P. H. Jordan himself of his improvement in the machine for Crushing and Grinding Corn

To all to whom these presents shall come

Be it known that I Anderson P. H. Jordan of the Town of Madisonville in the County of Monroe and State of Tennessee have invented a new and useful improvement in the corn crusher and grinder and that the following is an exact description of the construction and operation of the said machine as improved by me
1st The Nut is cast iron something in the shape like the nut of the coffee mill, about ~~two~~ inches and a half in length and about five inches in diameter at the large end and three and a half at the small end with a hole through the ~~center~~ one inch square it is furnished something like the coffee mill. The furrow at the small end being near a half inch deep and gradually becoming shallower towards the large end where they are between eighth and quarter of an inch deep beginning at the small end and meeting the large end near you the furrow should incline from right to left about one fourth the round. 2nd The Shell or pit in which the nut works is also cast iron made smooth in shape like the nut only it is hollow for the nut to work in and it is furnished on the inside on the same principal of the nut at the small end of the hollow of the shell is about a half inch larger than the small end of the nut. That is to say the corn and the crushed cob may have room to enter. Connected with the small end of the shell is and cast solid with it is contained a half round of metal about nine inches in length and hollowed to the same size of the small

end of the shell has also formed with ~~that~~ ~~that~~ frame, running the whole length and about half an inch deep, in this part the timber bar works. 3rd The bar of wrought iron, forming the first end of this bar is one inch square, on this is fixed the balance wheel. On the next four inches a judgement is formed, the next eight inches of the bar is to be made three inches broad and half an inch thick twisted from right to left half round. This part of the bar works in the open part of the shell. Then four inches of the bar is to be one inch square. On this part the nut is to be confined being well turned to the center. On the next three inches the second judgement is formed. Then six inches is to be one inch square on this part of the bar the wallower is fixed if propell'd by Horse or water power if by hand a pin is to be fixed in one arm of the balance wheel to form a crank. on the last two inches of the bar a judgement is formed which enters the back plate and is met by a screw of temper from which makes the machine work fine or coarse.

4th The frame is made as follows. first the sills are about three and a half feet long, four by six inches. the sills are connected by one or two cross pieces about two feet between the sills. in these sills are set four posts, four by five inches two on each sill. the posts are about fifteen inches between the sills and plates and eighteen inches apart. On the top of the posts are two more pieces which may be called plates. These plates are to be four by six inches one of them being split the broad way forming two pieces three by four, in the center between the two an inch is to be formed for the first judgement in the bar. these last mentioned pieces make one plate. The first judgement working between them and the tenants of two post passing through both pieces are to be keyed on the top. The plates are connected by two pieces two feet between the tenants nine inches apart. between the last described pieces the shell is to be firmly fixed so that it can not move out of its place. this is done by letting the open end of the shell into the split plate about half an inch. the other end is made fast by two pieces of iron with holes in each end one by two inches. these pieces, about two inches wide are bent in the middle so as to fit the shell, their ends extending across the pieces that support the shell. in each of these pieces of timber is made fast a screw with two taps, each three turns. this passes through the holes in the clamp, 10 pieces of iron made to fit the shell with one tap below.

and one above by this means the shell is easily turned out and also made secure behind the end a piece of timber or pole with an notch formed to receive the second jaw upon the bar and to prevent it from springing - 3rd. A balance wheel three feet in diameter is to be made of timber three inches thick and placed on one the first end of the bar. This prevents the check motion in crushing of the cob - 4th. The hopper is like that of a Grid Mill except the sides and the balance wheel which must be square to clear the wheel. The hopper is to be placed over the open part of the shell where the corn is received and crushed until it passes into the grinding part where it is made fine enough for stock feeding

The above described improvement consists in the uniting of the nut to the timbered bar and upon this union the patent is claimed
